GAME BOARD

Clinton L. Mohler, 7 Venetian Circle,
Daytona Beach, Fla.

Filed July 5, 1963, Ser. No. 75,681

Term of patent 14 years

(Cl. D34—5)

FIG-1

FIG-2

FIGURE 1 is a top plan view of the game board showing my new design; and

FIGURE 2 is a side elevational view, partially in cross-section, thereof.

The characteristic features of my design reside in the combination on a game board of a series of apertures in an eight leaf clover-like arrangement having a hemisphere configuration projecting from the center of each leaf to form a circle of said hemispheres, all as shown.

I claim:

The ornamental design for a game board, substantially as shown and described.
